The ornamental design for a cleaning brush rod, as shown and described.

DESCRIPTION

FIG. 1 is a front, right and top perspective view of a cleaning brush rod showing my design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is an enlarged top plan view thereof;

FIG. 8 is an enlarged bottom plan view thereof;

FIG. 9 is an enlarged view of portion 9 shown in FIG. 1;

FIG. 10 is an enlarged view of portion 10 shown in FIG. 1; and,

FIG. 11 is an enlarged view of portion 11 shown in FIG. 2. The broken lines are included for the purpose of illustrating portions of the cleaning brush rod that form no part of the claimed design. The dot-dash broken lines in the figures show the cutoff boundaries for the enlarged detailed portion views and form no part of the claimed design.
